(57) **CLAIM**

The ornamental design of a structural frame, as shown and described.

DESCRIPTION

FIG. 1 is a front, top perspective view of a structural frame comprising a first embodiment of a new, original, and ornamental design;

FIG. 2 is a left side elevational view of a structural frame comprising a first embodiment of a new, original, and ornamental design;

FIG. 3 is a right side elevational view of a structural frame comprising a first embodiment of a new, original, and ornamental design;

FIG. 4 is a front elevational view of a structural frame comprising a first embodiment of a new, original, and ornamental design;

FIG. 5 is a back elevational view of a structural frame comprising a first embodiment of a new, original, and ornamental design;

FIG. 6 is a top view of a structural frame comprising a first embodiment of a new, original, and ornamental design;

FIG. 7 is a bottom view of a structural frame comprising a first embodiment of a new, original, and ornamental design;

FIG. 8 is a front, top perspective view of a structural frame comprising a second embodiment of a new, original, and ornamental design;

FIG. 9 is a left side elevational view of a structural frame comprising a second embodiment of a new, original, and ornamental design;

FIG. 10 is a right side elevational view of a structural frame comprising a second embodiment of a new, original, and ornamental design;

FIG. 11 is a front elevational view of a structural frame comprising a second embodiment of a new, original, and ornamental design;

FIG. 12 is a back elevational view of a structural frame comprising a second embodiment of a new, original, and ornamental design;

FIG. 13 is a top view of a structural frame comprising a second embodiment of a new, original, and ornamental design; and,

FIG. 14 is a bottom view of a structural frame comprising a second embodiment of a new, original, and ornamental design.

The new, original, and ornamental design of the structural frame is contemplated to be a repeatable single segment capable of being stacked at the top and/or bottom surfaces to continue an unbroken/broken surface pattern of the right, left, front and back sides.
